Attorney.

Patented Nov. 2, 1926.

UNITED STATES PATENT OFFICE.

PAUL NICHOLAY, OF DETROIT, MICHIGAN, ASSIGNOR, BY DIRECT AND MESNE ASSIGNMENTS, TO DECELECO, INC., OF DETROIT, MICHIGAN, A CORPORATION OF MICHIGAN.

DETACHABLE BARRIER FOR HIGH-TENSION ELECTRIC CONDUCTORS AND APPARATUS.

Application filed January 7, 1924, Serial No. 684,753. Renewed September 27, 1926.

This invention relates to barriers between high tension conductors and apparatus in electric power plants and the like, and has for its primary object the provision of a barrier formed of demountable sections of insulating materials that may be readily assembled or dismantled at will.

Another object of my invention is the construction of barrier sections of fire proof as well as electric insulating materials arranged to interlock one with another and to be suspended or supported from ceiling, floor or side wall.

It has long been a desideratum among architects and electrical engineers to obviate the necessity of constructing high tension barriers of concrete or masonry at the time the power house is built. This method is both costly and inflexible, resulting in heavy, massive barriers that limit the disposition of conductors and apparatus to the plan pre-conceived before the building was erected. A re-arrangement to accommodate new apparatus or more efficiently utilize the building cannot be accomplished without demolishing large portions of the walls and flooring.

My invention overcomes these difficulties, providing a barrier combining electrical efficiency with lightness of weight and which can be quickly and inexpensively installed and removed whenever desired without being demolished.

Other objects and advantages will be apparent from the following description, wherein reference is made to the accompanying drawings illustrating preferred embodiments of my invention and wherein similar reference numerals designate similar parts throughout the several views.

In the drawings:

Fig. 1 is a detail sectional view through one side wall, floor and ceiling of a room in a power house.

Fig. 2 is an elevation of the disclosure in Fig. 1, looking from the right of Fig. 1.

Fig. 3 is a detail elevation showing the manner of suspending barrier sections from a ceiling or the like.

Figs. 4 and 5 are detail sectional views taken respectively on the lines 4—4 and 5—5 in Fig. 3.

Fig. 6 is a detail elevation, showing the manner of suspending barrier sections adja-

cent a side wall, to which they may be also supported.

Figs. 7 and 8 are detail sectional views taken respectively on the lines 7—7 and 8—8 in Fig. 6.

Referring now to the drawings, the numeral 5 designates the floor of an electric power plant, and the numerals 6 and 7 the side wall and ceiling of a room therein. An electric power plant is shown by way of example because there are located electrical apparatus and conductors adapted to carry high tension loads and accordingly the need of barriers involving the principles of this invention are particularly useful. It is to be understood, however, that my barriers are also useful in other locations—in fact, wherever high tension conductors or apparatus are installed.

In Figs. 1 and 2 a plurality of electric apparatus 8 and bus bars 9 are separated by barriers 10 so as to isolate the several electric members, and also to insulate them against possible arcing. Each barrier is formed of a plurality of demountable sections 11 formed of fire proof as well as electric insulating materials, such as tile, terra cotta, concrete, gypsum, or the like, and arranged to be detachably secured to a horizontal or vertical portion of the power plant, such as the ceiling 7 or side wall 6. The sections may also be formed with interlocking portions to insure accurate alignment and also to aid in preventing accidental openings between sections. As best illustrated in Figs. 5 and 7, the opposite side edges of the sections 11 are formed with interfitting tongues and grooves 12 and 13 respectively. Each section is preferably formed with parallel ribs 14 of greater thickness than the remaining portions of the section, so as to give a panel effect and also to provide portions of sufficient thickness to permit the provision of apertures throughout the section for the reception of detachable bolts or other securing elements of non-insulating material. As best shown in Figs. 3—8, certain of the ribs are apertured to permit the passage of elongated bolts 15, one extremity of which is embedded or otherwise suitably secured in the ceiling or other walls of the power plant, and are threaded at their opposite extremities to receive nuts 16 or other detachable means for locking the sections on the bolts.

100
105

In Fig. 3 a single section is shown suspended from the ceiling 7 by means of a bolt 15, while in Fig. 6 is shown the abutting horizontal edges of upper and lower aligned sections adapted to be suspended from the ceiling on the same elongated bolt 15^a. It will be apparent that, by aligning the apertures in the ribbed portions of the sections, as many sections as desired can be suspended from a ceiling or other horizontal support. If desired the barrier sections can also be supported from the vertical side wall 6 by means of tie rods 17 extending from the wall to a lug 18 on the free edge of the lowermost section 11 of the barrier, a nut 19 or the like being threaded upon the free extremity of the tie rod. It will also be apparent that by extending the bolts 15 in a horizontal direction from a side wall or other vertical support, individual sections can be supported directly against the side wall.

From the above it is believed to be apparent that I have provided barriers of fire proof as well as electric insulating materials that are capable of ready installation at any desired location, the alignment of adjacent barriers being automatic and the mounting of the barrier sections being easily understood by an ordinary mechanic or builder. The barrier will retain its position as long as desired, and can then be quickly dismantled without demolishing the barrier sections or the adjacent walls. Moreover, a single section or a group of sections can be removed at will.

The provision of the securing apertures within thickened ribs permits the insulation of the bolts or other securing elements without weakening the barrier, and the provision of thinner panels between adjacent ribs permits the ready breaking away of one panel should it be desirable to permit the passage of cross members through barriers already erected.

While it will be apparent that the illustrated embodiments of my invention herein

disclosed are well calculated to adequately fulfill the objects and advantages primarily stated, it is to be understood that the invention is susceptible to variation, modification and change within the spirit and scope of the subjoined claims.

Having described my invention, I claim

1. A barrier between electric conductors and apparatus comprising a plurality of demountable sections of insulating material, and means extending longitudinally through the sections for detachably connecting the sections to horizontal or vertical supporting members whereby each section may be separately removed.

2. A barrier between conductors and apparatus in electric power plants comprising a plurality of interlocking sections of fire proof and electric insulating materials, the sections being provided with apertures extending from edge to edge to receive securing elements.

3. A barrier between conductors and apparatus in electric power plants comprising a plurality of interlocking sections of fire proof and electric insulating materials, the sections being formed with apertures parallel to their faces, and securing elements adapted to be fixed to a wall of the power plant and to extend through said apertures.

4. A barrier between conductors and apparatus in electric power plants comprising a plurality of sections formed of fire proof and electric insulating materials, each section being formed with parallel ribs of greater width than the remainder of the section, and certain of said ribs being provided with apertures parallel with their faces to receive securing elements, and securing elements adapted to extend through said apertures and be fixed upon a wall of the power plant.

In witness whereof I hereunto set my hand.

PAUL NICHOLAY.
